UNITED STATES PATENT OFFICE.

THOMAS J. HENRY, OF SCRANTON, PENNSYLVANIA.

RAILROAD TIE.

Application filed June 4, 1927. Serial No. 196,538.

This invention relates to railroad ties and more particularly to the construction of a concrete tie embodying means for attaching the rail thereto.

5 An important object of the invention is to provide a device of this character which will provide a very rigid and positive connection between the tie and rail which may be readily placed or removed and which 10 will have no tendency to loosen, due to the vibration to which such devices are subjected.

A further object of the invention is to provide a device of this character, wherein the 15 tie is reinforced and the reinforcing elements serve to prevent any tendency to dislodgment or displacement of the securing element.

These and other objects I attain by the construction shown in the accompanying 20 drawings, wherein for the purpose of illustration is shown a preferred embodiment of my invention and wherein:—

Figure 1 is a plan view partially broken away of a railroad tie constructed in accordance with my invention;

Figure 2 is a side elevation thereof;

Figure 3 is a section on the line 3—3 of Figure 2;

Figure 4 is a vertical sectional view 30 through the sleeve and lock bolt;

Figure 5 is a side elevation thereof;

Figure 6 is a plan view thereof;

Figure 7 is a transverse sectional view therethrough.

35 Referring now more particularly to the drawings, the numeral 10 generally designates a concrete tie, which is preferably specially treated to render the same water and erosion resistant. Each end of the tie

40 has embedded therein a pair of vertically extending cylinders 11 which are interiorly threaded and are provided intermediate their ends upon their exteriors with triangular diametrically opposed anchoring webs 12.

45 The cylinders 11 are preferably four in number, a pair of these cylinders being arranged at each end of the tie and the cylinders of each pair being spaced longitudinally of the tie from one another a distance equal to the

50 width of a rail base B and being likewise spaced from one another transversely of the tie. Embedded in the tie are reinforcing elements 13 and 14, of which the reinforcing elements 13 extend longitudinally of the tie

55 and are co-extensive therewith and the reinforcing element extend transversely of the tie

of the entire width thereof. The reinforcing elements 13 are preferably four in number and are arranged in upper and lower pairs, of which the upper pair are arranged above 60 the level of the anchoring webs 12 and the lower pair below the level of the anchoring webs 12 of the cylinder 11. The reinforcing elements 14 are preferably eight in number and are arranged in groups of four at 65 opposite ends of the tie and of each group of four, one pair is arranged above and the other below the level of the anchoring web 12.

Associated with each cylinder is a bolt, 70 the threaded shank 15 of which is adapted to coact with the threaded interior of the cylinder and this bolt has a square head 16 whereby it may be engaged with a wrench to seat it in the cylinder. Immediately beneath the head, each bolt has a flange 17, the under surface of which is conical and has an inclination to the axis of the bolt similar to that of the upper surface of the rail base B to the vertical. This flange has formed 80 therethrough rectangular openings 18 for the passage of a key, each opening 18 having one face thereof coplanar with a facet of the head. The head has extending therethrough a plurality of bores 19, which are perpendicularly related to the facets and are adapted to receive a cotter pin 20 extended through an opening 21 formed in a key 22 extended through one of the openings 18. The upper end of the cylinder 11 has formed 90 in its interior wall a keyway 23, for the reception of the lower end of this key.

In the use of the device, after the rails have been properly seated, the bolts are placed in position and screwed down until 95 the rails are firmly engaged with the upper surface of the tie. An opening 18 of the flange 17 is aligned with the keyway 23 and the key 22 inserted to lock the bolt and sleeve against relative rotation. When the key is 100 fully seated, the cotter pin 20 is inserted through the opening 21 of the bolt and an opening 19 of the head to lock the key against displacement. The key employed is preferably provided at its upper end with a 105 cutting head 24 beneath which an implement may be engaged to withdraw the key when it is desired to remove the bolt.

It will be obvious that by use of a tie of this character, application and removal of 110 the rails is greatly facilitated and a positive lock provided against any movement thereof.

A device of this character may be very readily and cheaply produced and will be very durable and efficient in service.

Since the construction hereinbefore set forth is capable of a certain range of change and modification without materially departing from the spirit of the invention, I do not limit myself to such specific structure except as hereinafter claimed.

10. I claim:—

1. In combination, a tie having embedded in opposite ends thereof interiorly threaded cylinders arranged in pairs at opposite ends of the tie and having the cylinders of each pair spaced longitudinally of the tie a distance at least equal to the width of the base of the rail to be seated on the tie, bolts adapted to be threaded into said cylinders and having flanges the under surfaces of which are adapted to seat upon the base of a rail applied to the tie and locking means extending through said flanges for engagement with the cylinders to hold the bolts against rotation.

2. In combination, a tie having embedded in opposite ends thereof interiorly threaded cylinders arranged in pairs at opposite ends of the tie and having the cylinders of each pair spaced longitudinally of the tie a distance at least equal to the width of the base of the rail to be seated on the tie, bolts adapted to be threaded into said cylinders and having flanges the under surfaces of which are adapted to seat upon the base of a rail applied to the tie, said flanges being formed with circumferentially spaced key receiving openings, the cylinder being provided in its upper end with a keyway and a key extending through one of the openings of each flange and engaged in the keyway of the corresponding cylinder.

3. In combination, a tie having embedded in opposite ends thereof interiorly threaded cylinders arranged in pairs at opposite ends of the tie and having the cylinders of each pair spaced longitudinally of the tie a distance at least equal to the width of the base of the rail to be seated on the tie, bolts adapted to be threaded into said cylinders and having flanges the under surfaces of which are adapted to seat upon the base of a

rail applied to the tie, said flanges being formed with circumferentially spaced key receiving openings, the cylinder being provided in its upper end with a keyway and a key extending through one of the openings of each flange and engaged in the keyway of the corresponding cylinder and means extending through the key and the upper end of the bolt for preventing vertical displacement of the key.

4. In combination, a tie having embedded in opposite ends thereof interiorly threaded cylinders arranged in pairs at opposite ends of the tie and having the cylinders of each pair spaced longitudinally of the tie a distance at least equal to the width of the base of the rail to be seated on the tie, bolts adapted to be threaded into said cylinders and having flanges the under surfaces of which are adapted to seat upon the base of a rail applied to the tie, said flanges being formed with circumferentially spaced key receiving openings, the cylinder being provided in its upper end with a keyway, a key extending through one of the openings of each flange and engaged in the keyway of the corresponding cylinder and means extending through the key and the upper end of the bolt for preventing vertical displacement of the key, said key having at its upper end a cutting head.

5. In combination, a tie having embedded in opposite ends thereof interiorly threaded cylinders arranged in pairs at opposite ends of the tie and having the cylinders of each pair spaced longitudinally of the tie a distance at least equal to the width of the base of the rail to be seated on the tie, bolts adapted to be threaded into said cylinders and having flanges the under surfaces of which are adapted to seat upon the base of a rail applied to the tie, locking means extending through said flanges for engagement with the cylinders to hold the bolts against rotation, said cylinders each having intermediate its ends at diametrically opposed points triangular anchoring flanges.

In testimony whereof I hereunto affix my signature.

THOMAS J. HENRY.
